CAP FOR TREE LIMB SUPPORTING ASSEMBLY

Louis P. Caldwell, Independence, and Preston C. Caldwell,
Kansas City, Mo.

Application November 15, 1954, Serial No. 33,104

Term of patent 7 years

(Cl. D35—3)

Fig. 1 is a side elevational view of the cap for tree limb supporting assembly, showing our new design;

Fig. 2 is a top plan view thereof; and

Fig. 3 is a bottom plan view of the cap for tree limb supporting assembly.

We claim:

The ornamental design for a cap for tree limb supporting assembly, as shown.
